FOREIGN PATENT DOCUMENTS

EM 001797135-0005 12/2010

Primary Examiner — Paula Allen Greene(74) *Attorney, Agent, or Firm* — SHUTTLEWORTH & INGERSOLL, PLC; Jason R. Sytsma(57) **CLAIM**

The ornamental design for a curved heart cremation urn, as shown and described.

DESCRIPTION

FIG. 1 a top perspective view of a curved heart cremation urn according to this disclosure;

FIG. 2 is a front view of the curved heart cremation urn of FIG. 1;

FIG. 3 is a back view of the curved heart cremation urn of FIG. 1;

FIG. 4 is a right side view of the curved heart cremation urn of FIG. 1;

FIG. 5 is a left side view of the curved heart cremation urn of FIG. 1;

FIG. 6 is a top view of the curved heart cremation urn of FIG. 1; and,

FIG. 7 is a bottom view of the curved heart cremation urn of FIG. 1.
